UNITED STATES PATENT OFFICE.

CECIL BENTHAM, OF MANCHESTER, ENGLAND, ASSIGNOR TO HENRY SIMON LIMITED,
OF MANCHESTER, ENGLAND.

APPARATUS FOR THE PNEUMATIC TRANSPORT OF GRAIN AND OTHER GRANULAR OR LIKE MATERIALS.

Application filed August 27, 1921. Serial No. 495,906.

To all whom it may concern:

Be it known that I, CECIL BENTHAM, a subject of the King of Great Britain and Ireland, and a resident of Manchester, in the county of Lancaster, England, have invented certain new and useful Improvements in or Connected with Apparatus for the Pneumatic Transport of Grain and other Granular or Like Materials, of which 10 the following is a specification.

This invention has reference to apparatus for the pneumatic transport of grain and other granular or like materials, the apparatus being of the kind in which the grain 15 or other material is delivered by suction into a vacuum-chamber receiver wherein is arranged a cyclone separator, the grain and heavier dust being discharged from the receiver through appropriate valves, or an air lock or seal, and the air and the lighter dust 20 passing into the cyclone separator, wherein the dust, or the greater proportion of it is separated from the air, and the separated dust passes out through an outlet at the base 25 of the cyclone, while the air passes out at the top to atmosphere or to the suction pump or the like.

In known apparatus of the said kind, the cyclone separator is arranged concentrically 30 within the receiver, and the base thereof communicates with the dust outlet by means of an inclined pipe or spout. The object of the invention is to provide an improved arrangement of cyclone separator whereby a 35 larger cyclone separator can be employed in a receiver of given size, without interfering with the efficiency of the latter, and a more direct delivery of the dust is obtained from the cyclone separator.

40 According to this invention, the cyclone separator, instead of being arranged concentrically in the receiver as hitherto, is arranged at an inclination to the axis of the receiver, with its base towards one side thereof away from the inlet for the grain or other material and air.

50 In the accompanying drawings Fig. 1 is a central vertical section, and Fig. 2 is a sectional plan of one arrangement of vacuum-chamber receiver and cyclone separator in accordance with the invention.

Referring to the drawings, the cyclone separator 1 is disposed in the receiver 2 at such an inclination to the axis of the latter,

that the tangential cowl or inlet 3 to its cylindrical upper part 4 is close to the wall of the receiver 2 at one side thereof, and its conical base 5 is close to the wall of the receiver 2 at the opposite side. Preferably, the inclination of the cyclone separator 1 is such that its axis intersects the plane of its upper end on the axis of the receiver 2 as shown in Fig. 1.

The receiver 2 is provided, as hitherto, with a conical or hoppered bottom 6 with an aperture in the wall of which, the base 5 of the cyclone separator communicates directly, or by means of a junction or throat piece 7. The aperture in the wall of the bottom 6 of the receiver 2 is provided on the outside with a fitting 8 for the connection of a pipe, spout or the like for leading the dust from the cyclone separator 1 to any required place. The fitting 8 may be provided with an inspection hole 9 fitted with a removable cover.

The inlet 10 for the entrance of the grain or other material to the receiver 2 opens tangentially to the latter, and is situated more or less vertically below the tangential cowl or inlet 3 to the upper part 4 of the cyclone separator 1 and opposite to the base of the latter. The bottom of the receiver 2 is provided with a central discharge aperture 11, for the discharge of the grain or other material and the heavier dust in the known way.

The tangential cowl or inlet 3 to the upper part 4 of the cyclone separator 1 is provided with a regulating valve which may conveniently be in the form of a flap 12 secured to a rotatable spindle 13 mounted in a bearing 14 on the interior wall of the upper part of the cyclone separator and a bearing 15 on the top cover 16 of the receiver 2. The upper end of the valve spindle 13 may be provided with a hand wheel 17 or other suitable means for adjustment, and a handled locking nut 18 for screwing up against the bearing 15 to clamp it in the required adjusted position.

In use a partial vacuum is created in the separator through suction in the conduit passing from the upper end of the separator through the upper wall 16 of the receiver 2. The inlet 10 extends into the body of grain or granular material which is to be transported, and the partial vacuum which is created in the inlet 10 and the receiver

through the latter's communication with the interior of the separator causes movement of the grain or granular material through the inlet 10 into the chamber of the receiver. 5 The grain or material entering the receiver is deflected by the inner walls of the receiver in a circular direction and owing to the slower movement of the air in the receiving chamber the velocity of the particles entering through the conduit 10 is partially decreased, with the result that the grain or heavier particles of dust will fall into the hoppered bottom and be discharged through the aperture 11 therein at suitable intervals. 10 The lighter particles of dust still held with the incoming air will rise in the receiver while passing circumferentially around the interior thereof, and will enter the separator through the inlet 3. The dust and air will circulate through the separator during which circulation the dust will be separated from the air and fall into the conical bottom, from which it will be discharged directly through the outlet spout 8. The air separated from the dust will pass outwardly through the conduit extending from the upper end of the separator through the upper wall of the receiver. The inspection window 9 enables one to observe the functioning of the separator. The valve in the inlet 3 of the separator provides a control of the suction transmitted to the chamber of the receiver.

What I claim as my invention and desire to secure by Letters Patent is:—

- 35 1. In apparatus for the pneumatic transport of grain and other granular or like materials, a vacuum-chamber receiver of the kind referred to a cyclone separator contained in said receiver and arranged at an inclination to the axis of the receiver with its base towards one side of the receiver and away from the inlet to the receiver for the grain or other material and air.
- 40 2. A vacuum-chamber receiver according to claim 1 wherein the base of the inclined cyclone separator opens through an aperture in the wall of the bottom of the receiver.
- 45 3. A vacuum chamber receiver comprising a casing into which grain or other granular and like materials are received, a cyclone separator arranged in said casing the axis thereof being inclined with relation to the

axis of the receiver, said separator being connected to discharge through an aperture in the bottom wall of the casing, a spout pipe on the outside of the casing forming a continuation of the separator, said spout pipe having an inspection window therein. 55 60

4. A vacuum-chamber receiver according to claim 1, wherein the inlet to the cyclone separator is provided with a valve operable from the outside of the receiver.

5. In apparatus for the pneumatic transport of grain and other granular or like materials, a vacuum-chamber casing with an aperture in its bottom wall, a cyclone separator contained within and communicating with said casing with its axis inclined to the axis of the casing, said separator having a conical bottom discharging directly through the aperture in the bottom wall of the casing, a material inlet leading to the casing, and an air discharge from the separator. 65 70 75

6. In apparatus for the pneumatic transport of grain and other granular or like materials, a vacuum-chamber casing with an aperture in its bottom wall, a cyclone separator contained within the casing with its axis inclined to the axis of the casing, said separator adjacent its upper end communicating with the casing and having a conical bottom discharging directly through the aperture in the bottom wall of the casing. 80 85

7. In apparatus for the pneumatic transport of grain and other granular or like materials, a vacuum-chamber casing, a cyclone separator contained within the casing, the axis thereof being inclined with relation to the axis of the receiver, the separator communicating with the interior of the casing adjacent its upper end and discharging at its lower end directly through a wall of the casing. 90 95 100

8. The apparatus as set forth in claim 7, and a valve operable from the exterior of the casing and controlling the communication between the separator and the interior of the casing.

9. The apparatus as set forth in claim 7 and a discharge conduit exteriorly of the casing through which the separator discharges, said conduit having therein an inspection window. 105

In witness whereof I have hereunto set my hand.

CECIL BENTHAM.
